FOLDING MACHINE

George Lautzenheiser, Bluffton, Ind., assignor to
Amos Neuhauser, Bluffton, Ind.

Application January 31, 1936, Serial No. 61,791

4 Claims. (Cl. 93—51)

The invention relates to folding machines and it is particularly directed to machines for folding paper boxes.

In the manufacture of paper board boxes of the folding type, the box blank is usually formed on a die which scores the sheet to define the side wall and corner sections. To set up the box it is necessary to first break down or weaken the score lines by folding the wall sections onto the bottom forming section of the blank. In some boxes the corner sections connect adjacent wall sections and each corner section is diagonally scored between the score lines that are common to it and to the adjacent wall sections, so that the corner section may collapse against one wall section when the box is set up.

Heretofore, in the preliminary folding operation to break down the scorings, each corner section is folded onto a wall section as the adjacent wall section is folded onto the bottom section. This only breaks down one score line of the corner section. It is necessary to fold the wall section having the corner sections thereof folded onto the bottom section and onto the opposite wall sections previously folded thereon. This operation breaks down the scoring between the corner sections and the latter sections but it does not weaken the diagonal scorings.

This weakening or breaking down of the scorings is generally done by the manufacturer and the blank when received by the customer will have two opposite walls folded onto the bottom with the corner sections folded onto the other wall sections and if the latter wall sections carry locking flaps, these flaps will be folded onto the folded corner sections. Unless all the scorings of the corner sections are previously broken down the corner sections will not readily collapse when the customer sets up the box by rocking the wall sections upwardly that have the corner sections folded thereon.

The object of my invention is to provide a machine that will accomplish the breaking down or weakening of the scorings which define the wall sections of a folding box blank and the scorings of the corner sections that connect adjacent wall sections of the blank and also other selected scorings thereof and thereby avoid all hand folding of the parts to accomplish the weakening of scorings.

The invention is illustrated in the accompanying drawings in which

Figure 1 is a front elevation of the machine.

Fig. 2 is a side elevation of the machine.

Fig. 3 is a plan view of the main frame or table.

Fig. 4 is a cross section on line 4—4 of Fig. 3.

Fig. 5 is a cross section in enlarged scale on line 5—5 of Fig. 2.

Fig. 6 is a cross section on line 6—6 of Fig. 5.

Fig. 7 is a side elevation of one of the corner elevating members.

Fig. 8 is a plan view of a box blank.

Fig. 9 is a fractional plan view of the table illustrating a box blank in position to be operated on.

Fig. 10 is a fractional plan view of the feed table illustrating the box in initially folded condition.

Fig. 11 is a cross section on line 11—11 of Fig. 10, illustrating the finger raising a corner section of a box blank.

Fig. 12 is a plan view of the flap folding member.

Fig. 13 is a plan view of a modified and simplified form of the die and Fig. 14 is a cross section on line 14—14 of Fig. 13.

In the drawings the machine is designed primarily to fold boxes of the type shown in Fig. 8, in which the blank is scored to form the bottom (or top) 1, the side sections 2, the end sections 3 and the corner sections 4. Each corner section has a diagonal scoring 5. On each end section there is a flap 6 having a locking flap 7 thereon and defined by the scoring 8 and the locking flaps 9 at the opposite ends of said flap 6, defined by the scorings 10. All of the scorings except 8 and 10 may be broken down or weakened by the illustrative machine, which folds the blank into the condition shown in Fig. 12.

The machine in general consists of the main frame 20 having a top or table 21. A frame 22 is mounted on the top at one side thereof and supports the shafts 23 and 24. A pulley 25 is loosely mounted on the shaft 23 and a clutch 26 is adapted to connect the pulley to said shaft. The pedal 27 mounted on a rock shaft 28 is operatively connected to the clutch by the rod 28'. A belt 29 connects the pulley 25 to the drive pulley 30, mounted on the shaft 24. A pulley 31 drives the shaft 24 and is itself driven by the belt 32 which is driven by an electric motor 33 or other source of power.

A crank disc 34 is secured to the shaft 23 and a crank arm 35 is connected to the disc and to a collar 36 attached to a plunger rod 37 that is longitudinally slidable in the bearings 38 formed on the frame 22. A plunger 39 is attached to the lower end of the rod 37 and approximates in outline the interior of the box to be operated on. It is evident that by depressing the pedal 27 the plunger 39 is caused to reciprocate vertically.

An opening 40 (Fig. 3) is formed in the top or

5

55

feed table 21 which will admit the plunger as it reciprocates. The opening in outline corresponds to the outline of the bottom of the box, or of the top of the lid or cover for the box. A feeding mechanism is mounted on the table 21 and consists of a frame having a slotted cross member 41 and two side members 42 having the grooved wheels or rollers 43 thereon which are adapted to ride on the tracks or rails 44 supported on the table 21. Two slotted bars 45 are adjustably attached to the member 41, the slots 45 therein affording longitudinal adjustment thereof and the slots 41a in the cross member 41 affording lateral adjustment of the bars 45. Each bar 45 has a locating plate or guide 46 thereon upon which a box blank is placed, the plates or guides 46 serving to center the blank relatively to the opening 48 in the table top.

Two arms (Figs. 1, 2) carry rollers 48 (Fig. 2) 20 at their upper ends which engage in the grooved brackets 49 that are attached to the side members 42. The opposite ends of the arms 48 are secured to a rock shaft 50 mounted on the main frame. An arm 51 is adjustably pivotally connected to one of the arms 47, the opposite end of the arm 51 being connected to an eccentric 52 suitably mounted on the drive shaft 53 that is supported on the frame 20. The arm 51, when operated by the drive shaft, causes the arms 47 to reciprocate the feeding mechanism and carry a box blank into correct position over the opening 48 and under the plunger 38.

A bevel gear 54 is mounted on the shaft 53 and meshes with a gear 55 secured to a shaft 56 that, at its upper end, is geared to the shaft 23 by all of which the shaft 53 is driven.

The flat box blank is deposited on the feeder when the latter is in its maximum retracted position. The end flaps 6 of the blank rest on the plates 46 (Figs. 3 and 9) that are attached to the side members 42 respectively of the feeder. As an aid in properly positioning the blank on the plates, each plate is upwardly and outwardly inclined at its outer side as indicated in Fig. 1 and 45 similarly inclined at its side facing the operator as indicated at 57. When the pedal is depressed the feeder carries the blank into position under the plunger and over the opening 48 in the feed table. The descending plunger contacts the bottom forming section of the blank and forces the blank through the opening 48, the wall of the opening causing the side and end-forming sections of the blank to fold upwardly on the score lines defining the contour of the bottom section. 55 I prefer to form the opening 48 in a die 58 that is removably supported in an opening 59 formed in the feed table 21 in order that the machine may fold various sizes of boxes, it being apparent that each size of box requires a corresponding opening 48 through which it may be forced by the plunger 38.

In order that the corner sections shall be collapsed inwardly I provide, adjacent to each corner of the opening 48, a finger 60 (Figs. 3, 9, 65 10, 11), which is disposed in a groove 61 formed in the plate 58 and is pivoted at one end therein. The opposite end of the finger is bevelled on its under side and its free end is so disposed that it will engage the corner section 4 of the blank close to the inner end of the diagonal scoring 5 in said section, the finger being aligned with the said scoring. Beneath each finger 60 there is a plunger 61 which engages the finger and its lower end is loosely engaged by a yoke 62. The yokes 62 70 for the plungers at one end of the opening 48 are

connected to the rock shaft 50 and the yokes at the opposite end of the opening are connected to the rock shaft 54. A lever 63 (Fig. 4) is secured to the shaft 50 and a crank 64 is secured to the shaft 54. A spring 65 is connected to the lower arm of the lever 63 and to the plate 58 or to the top 21, and a link 66 is pivoted to the upper arm of the lever 63 and to the crank 64. A bar 67 is pivoted to the crank 64 and its opposite end is pivoted to a pivoted shoe 68 which contacts a cam 71 (Fig. 1) mounted on the shaft 56. The rotating cam 71 causes the bar 67 to reciprocate and rock both shafts 50, 54 which cause the fingers 60 to rock upwardly simultaneously under the corner sections 4 of the box blanks and initiate the inwardly collapsing movement of said sections on their respective scorings. In Fig. 11 a corner section 4 is shown in a partially collapsed condition occasioned by the finger 60 so that the downward movement of the blank 20 through the opening 48 will cause the corner sections to completely collapse as shown in Fig. 10. It is not desirable in the type of box illustrated to initially break down the scorings 5 and 10 defining the locking flaps 1 and 8. To prevent 25 the folding of the flaps 1 at the opening 48 I provide the slots 72 in the plate 58 at each corner of the opening 48 through which the flaps 1 will pass as the plunger forces the blank through the said opening.

The box blank, after it passes through the opening 48, is guided in its descent by the bars 73 which retain the side walls 2 in substantially upright position until the box contacts the intermediate table 74. A notch or other abutment 75 is formed in each guide at the proper point so that the upper edges of the side walls of the box will engage the same when the box reaches the table 74 and prevent it from rising with the plunger. The end walls of the box are not necessarily supported, hence in the descent of the box after it leaves the opening 48, the end walls swing more or less to their initial position relatively to the bottom section 1.

The next step is to fold the box into the condition shown in Fig. 12, that is, the condition in which it is to be delivered to the customer. To accomplish this step I mount a series of rollers 76 (Fig. 5) of suitable number in slots in the table 74. Each roller frictionally engages a roller 77 above it. The rollers 76 are simultaneously driven by the shaft 53, through the chain 78, the shaft 79 and the gearing 80 connecting the shaft to the shaft of the said rollers. The rollers 77 are spring opposed to accommodate various thicknesses of material. A second set of rollers 81, 82, is mounted in the brackets 83 carried by the table 74. Each of the rollers 81 frictionally engages a short spring opposed roller 84 and the roller 82 opposes the roller 83. The roller 82 is driven by the chain or belt 85 which is driven by the shaft 53. The gearing 81 causes the roller 82 to drive the rollers 81.

A pusher 86 is slidably mounted on the table 74 and carries at its forward side a downwardly bent plate 88 which, when the pusher is moved toward the first pair of rollers, will engage the adjacent side wall of the box, as the pusher moves the box toward said pair of rollers, and turns it downwardly onto the bottom section of the box so that it will pass between the rollers. The opposite side wall of the box is forced down inwardly by the rollers. Adjacent the opposite ends of the upper rollers are two guides 89 which 75

are mounted on the standards 91 that are adjustably mounted on the table 74. Each guide slopes downwardly on each side of its supporting standard and it is also bent or curved inwardly so that their forward ends are much nearer to each other than their opposite ends. These guides are adapted to be engaged by the end sections of the box as the box travels through the several rollers. The said end sections first travel up the inclined portion of the guides and in doing so are caused to fold inwardly. As they travel down the declined portion of the guides the tapering or converging guides cause the end sections to fold over onto the folded side sections of the box by the time the box has reached the last pair of rollers by which rollers the end sections are ironed flat and the folded box is delivered from the last pair of rollers onto a plate 92 (Fig. 5) that is secured to a rock shaft 93 and operatively connected to a convenient part of the machine for oscillation so as to swing the box to a vertical position on edge on the carrier 94.

A lever 95 (Fig. 6) is pivoted to the main frame and its upper end is suitably pivotally connected to the pusher 88, as by engaging said end in a slot 96 in the pusher. A rod 97 is adjustably secured at one end to the lever 95 and its opposite end is connected to an eccentric 98 mounted on the shaft 53. The reciprocating rod 97 causes the reciprocation of the pusher at the proper time.

The adjustable guards 99 assure that the box, now having its side sections folded over onto its bottom section by the first pair of rollers, will pass under the second pair of rollers while the end sections are being turned upwardly by the guides 88.

A simple form of die 100 is shown in Figs. 13, 14, which may be substituted for the die 58. In this form of die the plate 101 is adapted to seat in the opening 59 in the table 21 and the opening 102 is formed in said plate, the walls of the plate about the opening being sloped downwardly inwardly. The corner between each two adjacent walls is not sloped downwardly but its top is flat and its side walls converge inwardly so as to form an abutment 103 that will engage the corner section of the box blank that rests on it and cause said section to fold inwardly as the plunger forces the blank through the opening 102 in the die, the side flaps of the blank being received by the slots 104 in the die so that said flaps are not folded. This form of die is much more simple than the die 58 as it eliminates the pivoted fingers 88 and their operating mechanisms. When

the die 100 is used the guides 73 will be carried by the table top 21.

What I claim is:

1. A machine for folding boxes having foldable side walls and collapsible corner sections integral with said walls, comprising means to engage and turn the walls simultaneously perpendicularly to the plane of the bottom or top wall of the box, means to engage the corner sections and cause them to fold inwardly as the walls move to break down the score lines of said sections and means to fold the turned walls inwardly and downwardly. 5

2. A machine for folding box blanks having foldable side walls and collapsible corner sections, and comprising a table having an opening in its top, the area of the opening corresponding to the area of the bottom or top of the box to be folded, means to force the box blank through said opening for turning the side walls perpendicularly to the plane of the bottom or top wall of the box blank, means adjacent to each corner of said opening adapted to engage the corner sections and cause them to fold inwardly as the blank passes through said opening, and means to subsequently fold said walls onto the bottom or top wall of the box. 10 20 25

3. A machine for folding box blanks having foldable side walls and collapsible corner sections and comprising a feed table, a die supported by the table and having an opening therein corresponding in outline to the bottom forming or top forming wall of the blank, means to feed the blanks successively onto the die, a plunger to engage the bottom or top forming wall of the blank and force the blank through the said opening whereby to turn upwardly the walls of said blank, a member at each corner of the opening to engage the corner sections and cause them to collapse inwardly as the blank is moved through said opening and means to fold the walls inwardly and downwardly. 30 35 40

4. A machine for folding box blanks having foldable side walls and diagonally scored corner sections integral with said walls and foldable thereon, and comprising means to engage and turn the side walls perpendicularly to the plane of the top or bottom wall, means to engage the corner sections and cause said sections to initially fold inwardly on the side wall sections and to be collapsed on the diagonal score lines under the influence of the turning movement of said walls, and means to fold said walls onto the top or bottom wall. 45 50 55

GEORGE LAUTZENHEISER. 55
